CLAIM

The ornamental design for eyewear, as shown and described.

DESCRIPTION

FIG. 1 is a perspective view of eyewear showing my new design;

FIG. 2 is another perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side perspective view thereof, the left side perspective view being a mirror image thereof; and,

FIG. 8 is an enlarged perspective view of a portion thereof as indicated by section 8—8 in FIG. 1.

The lens of the eyewear of my new design may be transparent, translucent, or reflective.
